UNITED STATES PATENT OFFICE.

ARTHUR HALE, OF BALTIMORE, MARYLAND, AND ROBERT H. NEWELL, OF MEDINA,
NEW YORK.

WASHABLE SLIPPER.

1,290,547.

Specification of Letters Patent.

Patented Jan. 7, 1919.

Application filed April 17, 1918. Serial No. 229,094.

To all whom it may concern:

Be it known that we, ARTHUR HALE and ROBERT H. NEWELL, both citizens of the United States, respectively residing at Baltimore and Medina, in the counties of Baltimore City and Orleans and States of Maryland and New York, have invented certain new and useful Improvements in Washable Slippers; and we do hereby declare the following to be a full, clear, and exact description of the invention, such as will enable others skilled in the art to which it appertains to make and use the same.

This invention relates to washable slippers and has for its object to provide an article of this character which will be comparatively inexpensive to construct, very easy to wash, and more comfortable in use than those heretofore proposed.

With these and other objects in view the invention consists in the novel details of construction and combination of parts more fully hereinafter disclosed and particularly pointed out in the claims.

Referring to the accompanying drawings forming a part of this specification in which like numerals designate like parts in all the views:—

Figure 1 is a diagrammatic longitudinal sectional view of a washable slipper made in accordance with this invention;

Fig. 2 is a view similar to Fig. 1 showing the parts in their partially assembled relation; and

Fig. 3 is a sectional view taken on the line 3—3 of Fig. 1 looking in the direction of the arrows.

1 indicates any suitable washable upper but preferably of a loosely woven crash-like material, and 2 any suitable outer sole of a washable material.

3 represents a washable reinforcing strip sewed to the rear edge 4 of the upper 1, and 5 a similar washable strip stitched to said upper and sole, and serving to unite the same as illustrated. It will be observed that the strips 3 and 5 meet at the points 6, as best illustrated in Fig. 3, but that the reinforcing strip 5 continues around the heel portion, and from said points 6 serves to secure the edges of the outer sole 2 to the edges of an inner sole 8. Said inner sole 8 is not only secured at its edges to said outer sole 2, around the heel portion as just described, but

55 it is further secured at its edges for a short

distance forward of the points 6 to the upper 1 as is indicated by the numeral 9, and the dotted lines in Fig. 3.

Forward of the points 9 the inner sole 8 is left free, as best shown in Fig. 2, and therefore, between said points 9 and the extreme rear or heel portion of the slipper there is formed what may be termed a rear pocket 10, into which may be readily slipped the rear end portion 12 of the stiffening or inner sole member 13 as shown. The forward end portion 14 of said stiffening member is readily slipped into the pocket 15 formed by bending over, or securing the piece 16 to said inner sole member; and the edges of said piece 16 are secured to the edges of the member 8 by the washable strip 17, while the extreme rear edge of the member 16 is finished off by the strip 18 as shown.

75 The parts except the stiffening member 13 being all made from a readily washable fabric material, and the said stiffening member itself being readily detachable and attachable, it is evident that slippers made in accordance with this invention may be washed as conveniently as any other article of wearing apparel. Further, it is preferred to make the stiffening member 13 of a fabric material having a washable, or celluloid like surface, so that it too may be kept at all times clean and sanitary.

What is claimed is:—

1. In readily washable footwear the combination of an upper member; an outer sole member secured to said upper member; an inner sole member secured for a portion of its length to the heel portion of said outer sole member to provide a pocket and a free forward end, said inner sole member also providing a continuous, unbroken, surface for the foot of the wearer from its heel to its toe portions; a second pocket carried by said free end; and a flexible readily attachable and detachable stiffening member located in said pockets between said inner and outer sole members, substantially as described.

2. In readily washable foot-wear the combination of an upper member; an outer sole member secured to said upper member; an inner sole member secured for a portion of its length to the heel portion of said outer sole member providing a pocket and a free forward end; a second pocket carried by said

free end; and a readily attachable and detachable stiffening member carried by said pockets, substantially as described.

3. In readily washable footwear the combination of an upper member; an outer sole member wider at its front portion than at its rear portion secured to said upper member; an inner sole member of substantially the same contour as said outer sole member secured for a portion of its length to the heel portion of said outer sole member to provide a pocket and a free forward end, said inner sole member also providing a continuous,

unbroken, surface for the foot of the wearer from its heel to its toe portions; a second pocket carried by said free end; and a flexible readily attachable and detachable stiffening member of substantially the same contour as said inner sole member located in said pockets between said inner and outer sole members, substantially as described.

In testimony whereof we affix our signatures.

ARTHUR HALE.
ROBERT H. NEWELL.
